UNITED STATES PATENT OFFICE.

JOHN B. HADAWAY, OF BROCKTON, MASSACHUSETTS.

SHOE-SEWING MACHINE.

No. 838,182.

Specification of Letters Patent.

Patented Dec. 11, 1906.

Application filed January 16, 1904. Serial No. 189,249.

To all whom it may concern:

Be it known that I, JOHN B. HADAWAY, a citizen of the United States, residing at Brockton, in the county of Plymouth and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

This invention relates to shoe-sewing machines having means for separating or indenting the stitches during the operation of sewing the sole of a shoe to the welt. In machines of this type as previously proposed the stitch-separating devices have been arranged to operate continuously during the operation of the sewing mechanism, so that in sewing a shoe the stitches would be separated along the entire seam. This is undesirable, as it is customary to separate the stitches only around the fore part of the shoe and to leave the seam smooth in the shank, which improves a more pleasing finish to the shoe.

It is the object of the present invention to produce a sewing-machine having stitch-separating means which may be thrown into or out of operation during the continued operation of the sewing instrumentalities, so that in sewing a shoe the portions of the seam at the shank may be left smooth, the stitch-separating device being inoperative during the formation of these portions of the seam, while the stitches around the fore part of the sole are separated in the usual manner by throwing the separating device into operation during the formation of this part of the seam.

To this end the invention consists in the improved sewing-machine hereinafter shown and described, and particularly defined in the claims.

The invention is applicable to all forms of welt-stitching machines irrespective of the nature of the stitches formed or the form or mode of operation of the sewing instrumentalities, and it may be embodied in a fair-stitch machine as well as in a lock-stitch machine.

The invention as illustrated in the drawings is embodied as an improvement in the

machine described and shown in Letters Patent of the United States, No. 616,314, granted to me December 20, 1898.

55

In the drawings, Figure 1 is a front elevation of a portion of a sewing-machine embodying the present invention. Fig. 2 is a plan view of the same, and Fig. 3 is a right-hand side elevation.

60

With the exception of the means for throwing the stitch-separating device into and out of operation the illustrated embodiment of the present invention is constructed like that of the above-mentioned Letters Patent. The stitch-forming mechanism is, as in the said patent, substantially like that shown and described in United States Patent No. 473,870, issued to the Goodyear Shoe Machinery Company as the assignee of Z. T. French and William C. Meyer and dated April 26, 1892, to which patent reference may be had for information relative to parts of the machine not shown in the accompanying drawings.

70

The sewing instrumentalities shown in the drawings comprise the needle 1, the awl 2, the work-rest 3, and the presser-foot 4, all constructed and operated as in the said Patent No. 473,870, with the exception of the modification of the presser-foot mechanism described in the said Patent No. 616,314. The needle is carried by a segment 5, loosely mounted on a stud 6, projecting from a portion 7 of the frame of the machine. The awl 85 is carried by a segment 8, loosely mounted on a stud 9, carried by the standard 10, secured to the feed-slide 11. The presser-foot is secured to a lever 12, pivoted on a stud 13, secured to a part 14 of the frame of the machine. The stitch-separating mechanism, with the exception of the actuating-cam, is all carried by a frame 20, fixed by set-screws 21 22 to extensions from the stud 13 and a stud 15, upon which the thread-lifter lever 16 is carried. The 95

stitch-separating tool 23 is carried by an arm 24, provided with a stem 25, mounted to oscillate in the arm 26, projecting from the frame 20. A lever 27, secured to the end of the stem 25, is connected by a link 28 with a cam-lever 29, pivoted upon a fulcrum-stud 30, mounted in the frame 20. The upper end of the cam-lever carries a roll 31, which bears against the periphery of a cam 32, secured to

100

the main shaft 33 of the sewing-machine. The periphery of the cam is circular, except for a short rise 34. A spring 39 bears against the frame 20 and the cam-lever 29 and tends to return the stitch-separating tool to its retracted position. The parts so far described operate substantially like the machine of the said Patent No. 616,314, the rise 34 on the cam 32 periodically actuating the stitch-separating tool through the connections described to cause it to swing forward and engage the welt of the shoe between the stitches, so as to separate the same by an indentation, this operation taking place while the needle and awl are withdrawn from the work and just before the awl enters the work to puncture and feed the same.

The means for throwing the stitch-separating mechanism into and out of operation comprise a hand-lever 40, mounted on a stud 41, secured to the frame 20. The hand-lever has a slot 42, embracing the fulcrum-stud 30, upon which the cam-lever is mounted. The slot 42 is curved eccentrically to the stud 41, so that when the hand-lever is drawn forward from the position shown in the drawings the fulcrum-stud 30 will be drawn toward the stud 41, the stud 30 being mounted loosely in an elongated hole 35 in the frame 20 and having a flange 36 and a washer 37, secured by a nut 38, for guiding it in the hole 35. The hand-lever is secured in place on the stud 41 by a nut 43 and a lock-nut 44, which may be adjusted so as to subject the lever to sufficient friction to prevent its accidental displacement from the position into which it is thrown by the operator. A screw 45, adjustably secured by a nut 46 in lug 47 on the arm 26, engages the lever 27 and through the link 28 prevents the cam-lever from swinging farther to the right than the position shown in the drawings. Consequently when the hand-lever is drawn forward, as described, the movement of the fulcrum-stud 30 draws the cam-roll out of contact with the cam, and the operation of the stitch-separating mechanism is thus interrupted without affecting the operation of the sewing mechanism, and the stitch-separating tool remains in its retracted position.

The present invention contemplates in its broader aspects any means for interrupting the operation of the stitch-separating device, whether by causing the actuation thereof to be interrupted or by preventing the separating-tool from coming in contact with the work.

In the operation of sewing a shoe upon this machine the seam is started at the heel and the hand-lever is drawn forward so as to throw the stitch-separating mechanism out of operation while the shank is being sewed. As soon as the fore part of the sole is reached the hand-lever is thrown back and the stitch-

separator indents the stitches around this part. The lever is again drawn forward when the other side of the shank is reached, so as to leave this part of the seam smooth.

The present invention is not limited in its application to the specific forms of sewing mechanism and stitch-separating mechanism described, and the means for throwing the stitch-separating mechanism into and out of operation may be embodied in many other forms broadly defined by the claims.

Having thus described my invention, I claim as new and desire to secure by Letters Patent of the United States—

1. A shoe-sewing machine, having, in combination, stitch-forming mechanism, a stitch-separating device, and means for throwing the stitch-separating device into and out of operation during the continued operation of the machine, substantially as described.

2. A shoe-sewing machine, having, in combination, stitch-forming mechanism, a stitch-separating device, mechanism for actuating the stitch-separating device, and means for interrupting the operation of the said actuating mechanism during the continued operation of the machine, substantially as described.

3. A shoe-sewing machine, having, in combination, stitch-forming devices, a stitch-separating device, mechanism for actuating the stitch-forming devices, independent mechanism for actuating the stitch-separating device, and means for throwing the stitch-separating device into and out of operation during the continued operation of the machine, substantially as described.

4. A shoe-sewing machine, having, in combination, stitch-forming mechanism, a stitch-separating device, means for actuating the latter including a lever mounted on a movable fulcrum, and means for moving the fulcrum to throw the stitch-separating device into and out of operation, substantially as described.

5. A shoe-sewing machine, having, in combination, stitch-forming mechanism including a needle and an awl, a stitch-separating device means for actuating the said device to engage the work while the needle and awl are withdrawn therefrom, and means for throwing the stitch-separating device into and out of operation during the continued operation of the machine, substantially as described.

6. A shoe-sewing machine, having, in combination, stitch-forming mechanism, a stitch-separating device, means for actuating the latter comprising a lever, a cam-roll carried thereby and a cam engaged by the cam-roll, and means for holding the cam-roll out of contact with the cam to interrupt the operation of the stitch-separating devices, substantially as described.

7. A shoe-sewing machine, having, in combination, stitch-forming mechanism, a stitch-

separating device, and independent means for actuating such device having provision for interrupting the separating operation thereof, substantially as described.

5 8. A shoe-sewing machine, having, in combination, stitch-forming mechanism, and stitch-separating means having provision for interrupting the separating operation thereof

10 during the continued operation of the machine, substantially as described.

In testimony whereof I affix my signature in presence of two witnesses.

JOHN B. HADAWAY.
